BY Alfred Meltzer, his ATT'Y.

UNITED STATES PATENT OFFICE.

HENRY C. DUENSING, OF BEECHER, ILLINOIS.

TRACTION-WHEEL.

SPECIFICATION forming part of Letters Patent No. 604,006, dated May 10, 1898.

Application filed August 14, 1897. Serial No. 648,226. (No model.)

To all whom it may concern:

Be it known that I, HENRY C. DUENSING, a citizen of the United States, residing at Beecher, in the county of Will and State of Illinois, have invented a new and useful Improvement in Traction-Wheels, of which the following is a specification.

My invention relates to traction-wheels, and particularly to means for preventing the accumulation of snow and ice on the tread of the wheel. Its object is to provide a construction in which the tread of a traction-wheel may be heated while the wheel is in motion, so as to prevent such accumulation. I attain this object by the mechanism illustrated in the accompanying drawings, in which—

Figure 1 is an elevation of a part of a traction-engine embodying my invention, showing part of the boiler and one of the wheels with steam connections. Fig. 2 is a vertical section on the line W W of Fig. 1 with the wheel turned so that the pipe 5 is in a vertical position. Fig. 3 is a cross-section of the rim of the wheel, taken on the line X X of Fig. 1. Fig. 4 is a vertical section of part of the rim of the wheel, taken on the line Y Y of Fig. 2.

The traction-wheel is provided with a hollow rim formed by fastening an outer rim or casing 2 upon the inner rim 4, leaving the airtight compartment 1 between same. A gasket 3 extends around the wheel between the two rims on either side, the rims being fastened together, compressing the gaskets, by means of the bolts 14. The bolts 14 also serve to secure the rims to the spokes 15.

The pipe 5, communicating with the compartment 1, is secured to the inner rim 4 and turns with the wheel, the lower part of the pipe revolving in its connection with the pipe 10. The connection between the pipes 5 and 10 comprises a stuffing-box 7 8. The pipe 5 is provided with ports 6, communicating with the pipe 10. The outer end of the pipe 5 is closed by a cap 9. The pipe 10 communicates with the boiler 11 and is provided with a cock 17 for controlling such communication.

The compartment 1 in the rim has therein a partition 13, near the pipe 5. On the side of the partition away from the pipe 5 a cock 12 is provided for discharging the exhaust.

The pipes 5 and 10 are removably secured

to the rim and boiler, respectively, so that same may be disconnected when not needed.

The operation of the device will be readily understood. When the wheel revolves on its axle 16, it turns the pipe 5 with same. The steam passes from the boiler into the pipe 10, thence through the pipe 5 into the hollow rim on one side of the partition 13, thence passing along the rim in the compartment 1 to the other side of the partition, where same condenses and where the exhaust may be discharged through the cock 12.

The advantages of my device will also be readily understood. Heretofore much difficulty has been experienced with traction-engines through the formation of ice on the tread of the wheel, especially where the tread is provided with projection 18, the ice either forming large lumps or forming a smooth surface between the projections, and thus materially interfering with the movement and power of the wheel. My device overcomes this objection by preventing the formation of ice while the engine is in operation and also providing convenient means for removing ice which may form upon the engine while same is not in use.

It will be seen that the details of construction may be considerably altered without departing from the spirit of my invention.

What I claim as my invention, and desire to secure by Letters Patent, is—

1. A traction-wheel having a hollow airtight rim, with a partition 13 therein, and a discharge-cock on one side of said partition opening out of the rim, in combination with steam connections communicating with said rim on the opposite side of the partition, and adapted to convey steam or hot air into said rim while the wheel is in motion, for the purposes specified.

2. A traction-wheel having a hollow airtight rim; in combination with a pipe 5 communicating therewith at one end, having its other end bent in line with the axle of the wheel, and having a port 6 therein; an airtight connection in which said other end is journaled; and a pipe 10 secured to said connection for conveying steam or hot air through the port 6 and into said rim, for the purposes specified.

3. A traction-wheel having a hollow, air-

tight rim with a partition 13 therein, and a discharge-cock on one side of said partition opening out of the rim; in combination with a pipe 5 communicating therewith at one end, 5 on the opposite side of the partition, having its other end bent in line with the axle of the wheel and having a port 6 therein; an air-tight connection in which said other end is journaled; and a pipe 10 secured to said connection for conveying steam or hot air through the port 6 and into said rim, for the purposes specified.

4. A traction-wheel having an inner rim 4

and an outer rim 2 secured to same and grooved so as to form an air-tight compartment between said rims, and a gasket 3 intervening said rims on either side, in combination with steam connections, adapted to convey steam or hot air into said compartment while the wheel is in motion, substantially as 20 and for the purposes specified.

HENRY C. DUENSING.
